ATOMIZER.

1,340,433.

Specification of Letters Patent. Patented May 18, 1920.

Application filed December 2, 1918. Serial No. 265,043.

To all whom it may concern:

Be it known that I, JOHN H. BEYNON, a citizen of the United States, residing at Ontario, in the county of San Bernardino and

5 State of California, have invented new and useful Improvements in Atomizers, of which the following is a specification.

This invention relates to improvements in atomizers.

10 One of the objects of this invention is to provide an atomizer in which the delivery tube may remain open but from which the liquid is effectively trapped against leakage irrespective of the position in which the atomizer may be placed or located by hand, and irrespective of the position which the atomizer may assume, accidentally or otherwise, in a traveling grip, the perfection of this feature being accomplished in the entire absence of stoppers and valves.

15 A further object of my invention is to provide an atomizer in which the only opening exterior thereto is provided by the delivery tube and wherein the reservoir is filled through said tube, all egress through said tube excepting the atomized spray being completely trapped.

20 A further object is to provide a trap chamber in surrounding relation with respect to the delivery tube, the latter having a trap portion, preferably perforated, through which drippings or other liquid which might have gained access to said tube will not only be trapped against discharge therethrough, but will be delivered to said chamber.

25 My invention also includes a novel form of partition adapted to coact with the reservoir whereby the liquid therein will be held against escape into said trap chamber in any un-atomizing or inoperative position in which the device might be disposed.

30 A further object of my invention is to dispose the air and liquid tubes in a novel relation with respect to the reservoir and the delivery tube, and in such relation with respect to the partition as to prevent the liquid from accidentally escaping or leaking through the liquid tube, from the reservoir and out through the delivery tube, notwithstanding the fact that the delivery tube is in normally open communication with the reservoir through said liquid tube.

35 My invention has many other objects and features which will be more fully described in connection with the accompanying draw-

ing, and which will be more particularly pointed out and ascertained in and by the appended claims.

In the drawing:

Figure 1, is a longitudinal vertical sectional view of an atomizer embodying the preferred form of my invention.

Fig. 2, is a similar view showing the atomizer in an upright or operative position.

Fig. 3, is a similar view showing the atomizer in an inverted position, these three positions illustrating the manner in which the liquid is retained in the reservoir.

Fig. 4, is a sectional view on line 4—4 of Fig. 1.

Fig. 5, is an enlarged sectional view of the base end of the atomizer showing the manner in which the free end of the distributor tube is supportedly mounted.

Like characters of reference designate similar parts throughout the different figures of the drawing.

As illustrated, 1 designates a unitary body in which the device of my invention is incorporated and which may be formed of glass or any other available material. This body is provided with a reservoir 2, of a cross section and length capable of containing a predetermined maximum quantity of liquid, which will be prescribed in the form of instruction, or indications on the atomizer, so that the liquid level will be substantially below the longitudinal axis of the reservoir when the latter is in a horizontal position. At its base or bulb end, the reservoir is provided with a flanged opening 3, to facilitate insertion of an air tube 4. A cork or other form of filler 5, surrounds the free end of a distributor tube 18, herein-after described, to support the same. A ferrule 6 may be fitted over the flange of said opening 3, and I cement or otherwise anchor the free end of the distributor tube 18, to said ferrule 6, as indicated at 6'. This also makes a leak proof connection between the open end of the tube 18 and the ferrule 6.

The air tube 4, is bulbous at 7, to spread the nipple 8, of a hand bulb 9, of the usual type, which constitutes the means for forcing air through said tube 4. It will be noted that the bulb 9 is not greater in diameter than the maximum diameter of any other part of the atomizer, therefore, the device of my invention is capable of being inserted into a cylindrical container, as indicated in dotted lines, without requiring any

off-set compartments and of cross section only slightly greater than the greatest cross section of the atomizer and uniform throughout its length.

5 The reservoir has a cupped base wall 10 which serves to stiffen the body, and from this base wall, the annular wall 11, which is shown octagonal, tapers toward the front of the atomizing body to a point of maximum convergence 12, from which it flares toward its juncture at 13 with the periphery of greatest diameter of a trap chamber 14. Thus it will be seen that the trap chamber 14 and the reservoir 2, are in contiguous, integral and end to end relation. From its maximum diameter, said trap chamber 14 tapers toward its juncture with a delivery tube 15, at 16. Rearwardly from its juncture with the reservoir 2, the chamber 14 tapers at 17 and is elongated to form a partition which is shown tubular in shape, as indicated at 18. This tubular partition 18 is axially disposed with respect to the reservoir 2, and has openings 19, thereto, 25 near the base thereof. It will be noted by reference to Fig. 1, that even in a horizontal position of the atomizer, the partition tube 18 is inaccessible for discharge of liquid therethrough, and when the atomizer is inverted, as shown in Fig. 3, the liquid seeks a position farther remote from the intake openings 19, of said tube. In this latter position, the juncture of the reservoir 2 with the chamber 14, forms the bottom 35 which supports the liquid which is housed between the tube 18 and the wall of the reservoir. Only in case of a longitudinal jolting movement in the horizontal position shown in Fig. 1, could the liquid enter the 40 partition tube 18, and then, what liquid did find ingress thereto, would, if the atomizer were inverted, merely flow into and be trapped by chamber 14. If the atomizer were again righted, the wall 17, which gently 45 merges into the partition tube 18, would guide the liquid into the latter from which it would discharge into the reservoir 2.

Thus it will be clear that with this novel combination of reservoir, partition and trap chamber the liquid will, under anything like normal conditions, be confined in the reservoir where it belongs, but that even if it should reach the trap chamber, it will be promptly returned to the reservoir whenever the atomizer is righted.

Reverting to the delivery tube 15, its discharge end 20 is exteriorly disposed with respect to the trap chamber 14, and it extends inwardly thereof and in axial relation thereto whereby that portion of the tube interior to said chamber will be in such ample spaced relation thereto as to effectively prevent any liquid in said chamber from egressing outwardly through said 65 tube or even entering said tube. Whereas,

any dripping resulting from the atomizing action, and which remained in said delivery tube, would be returned to said chamber 14. It will be noted that the delivery tube 15 is in alined relation with the partition tube 70 18, and is therefore in open communication with the reservoir through said tube 18. One of the reasons for this specific disposition of the delivery tube 15, is to facilitate discharge of the atomizing tubes into said 75 delivery tube 15, and a further reason is to permit the intake end 21, of the delivery tube 15 to house the atomizing ends of the liquid and air tubes, as will presently appear. 80

A further and distinct feature of my invention is to provide the delivery tube 15 with a trap, and in the preferred form, this trap is perforated in a manner to deliver to the trap chamber 14 if the atomizer is in 85 other than an operative or upright position.

Between its ends, and inside of the chamber 14, the tube 15 is flared at 22, in annular formation outwardly from its prevailing 90 cross section. This alone, would serve to catch any liquid that entered the tube 15 but it would retain it until the atomizer was righted. Therefore, in order to provide for constant drainage of this trap, I 95 provide the same with a series of annular perforations 23. These holes 23 are not located in the diametrical crest of the flare of this trap, but somewhat rearwardly thereof with respect to the direction of flow 100 of the atomized liquid. Thus, instead of initiating the force of the air blast from the air tube by permitting leakage into the trap chamber, the holes open to the tube 15 rearwardly with respect to the direction of the 105 blast and merely serve to permit of entrained streams of air to be induced through said holes 23, as a result of the air stream from tube 4. If the holes 23 were in a facing position to the approaching blast from tube 4, a portion of the force of such blast would be lost through said holes. Thus I 110 am enabled to provide a drainage trap in the delivery tube without reducing the force of the air blast therethrough. 115

A liquid tube 24 is advisedly connected in supported relation with the air tube 4, alongside of which it extends, and this connection may be effected by cement or any other suitable expedient. This liquid tube 120 24 has its intake end 25 disposed in open communication with the reservoir 2, near the base thereof, so that it will be in receiving relation to the liquid therein at all times when a sufficient supply is present, 125 and when the atomizer is in an upright position. The discharge end of the liquid tube is curved into atomizing relation with the discharge end 27 of the air tube. The liquid tube is provided with a bore of uni- 130

form cross section throughout its length and the only resistance offered to the flow of liquid therethrough is the final curve at the discharge end. It is the object to make the bore so small, that liquid such as oil, would have too much friction to flow therethrough by gravity, even if the reservoir were filled to a point above the required amount, but the bore will not be reduced to such an extent as to restrict the flow therethrough under induction of the air stream from tube 4.

A further feature is to extend the discharge ends of tubes 24 and 4 into the intake end of the delivery tube in such a manner that the latter will house the same as regards their atomizing action. Because of the body of air in the trap chamber which will normally be quiescent, a more responsive atomizing action as a result of operation of the bulb 9, can be had by protecting the atomizing spray with the delivery tube and confining it therein. Of course, the air in chamber 14 will be set in motion as a result of the atomizing action but it will not interfere as an abutment in front of the discharge ends of tubes 24 and 4. Rather will it supply entrained flows of air not only through holes 23 but through end 21, replenishment of air to chamber 14 being effected during intervals between contractions of bulb 9. Thus practically the full force and effect of the blast from tube 4 will be available not only to induce a flow through liquid tube 24, but to also force the atomized particles outwardly through the delivery tube.

While I have shown the discharge end of the delivery tube shaped especially for nasal use, it will be obvious that the contour can be varied at will to meet the requirements of throat use.

Now it will be seen that one of the great advantages of my atomizer is that all parts thereof are concentric from a common longitudinal axis, there being no parts eccentric or off-set from such axis, therefore, the atomizer can be laid down on a dresser in any position and it is capable of being placed in a container of uniform cross section with a bore only so slightly in excess of the diameter of the largest part of the atomizer as to permit the latter to be freely inserted therein. A traveler can place this atomizer in a grip or traveling bag without fear of leakage, either with or without a container, and I avoid the cost of valves such as now are used to prevent leakage and which frequently become turned into an open position as a result of the jars and jolts incident to carrying an atomizer in a traveling bag.

It will be seen that the novel mounting of the free end of the partition tube in the cork stopper, and by its anchorage with the ferrule, that what would otherwise make the

juncture at 13, a point of weakness, is wholly avoided. A cork ring 5' may be employed to properly support the air tube 4, in place in the partition tube 18. It will be understood that when the parts are once assembled, it will never be necessary to remove the various tubes from the body 1. The bulb 9, will be readily removable for the purpose of sterilizing the body 1. Therefore, the cork rings and the ferrule are not to be considered in the light of removable stoppers.

In order to inform the user as to the predetermined maximum quantity of liquid beyond which the reservoir should not be charged, the base of the reservoir, if of glass, may be ground, colored or otherwise differentiated from the remainder of the reservoir so that when the liquid reaches the line of demarcation, in filling the atomizer, the user will know that fact when the liquid becomes visible above such line. While it is desirable and advantageous not to over charge the reservoir, still, such over charge if not extreme, would not cause the atomizer to leak out through the delivery tube since the trap chamber 14 would always catch the over-flow. However, in an atomizer, as in all other devices, certain limitations are controlling in its most efficient operation and use, and the public soon learns the advantages of following instructions.

It is believed that the advantages and utility of my invention will be fully understood from the foregoing description, and while I have herein shown and described one specific form of my invention, I do not wish to be limited thereto except for such limitations as the claims may import.

I claim:

1. In an atomizer, a unitary body provided with a supply reservoir, a liquid tube having an intake end opening to said reservoir and extending longitudinally of the latter and having a discharge end, an air tube extending through said reservoir and having a discharge end in atomizing relation to the discharge end of said liquid tube, a trap chamber contiguous with said reservoir and a partition tube housing said liquid and air tubes and open at one of its ends to said reservoir near the base of the latter and closing communication between said chamber and reservoir except through the open reservoir base end of said partition tube, a delivery tube housing the discharge ends of said liquid and air tubes and extending longitudinally through said chamber and having a discharge end exteriorly of said chamber, and means connected with said air tube for forcing air therethrough.

2. In an atomizer, a unitary body provided with a supply reservoir, a liquid tube having an intake end opening to said reservoir and extending longitudinally of the lat-

105

110

115

120

125

130

ter and having a discharge end, an air tube in supporting connection with said liquid tube and extending through said reservoir and having a discharge end in atomizing relation with the discharge end of said liquid tube and said air tube being supportedly connected with said reservoir, a trap chamber formed integral with and being in contiguous relation with said reservoir and 5 a partition tube housing said liquid and air tubes and extending longitudinally of said reservoir toward the base thereof and being open thereto at said base thereby closing communication between said chamber and 10 reservoir except through the reservoir base end of said partition tube, a delivery tube formed integral with said chamber and housing the atomizing ends of said liquid and air tubes and having a discharge end 15 exterior to said chamber, said delivery tube having an annular perforated trap flare between its ends and inside of said chamber and said flare being beyond the atomizing ends of said liquid and air tubes with respect 20 to the direction of flow therethrough, and means connected with said air tube for forcing air therethrough.

3. In an atomizer, a reservoir, a trap chamber and a partition located to prevent 30 communication between said chamber and reservoir except near the base of the latter, a liquid tube having an intake end opening to the liquid in said reservoir and having a discharge end projecting into said chamber, 35 an air tube extending through said reservoir and having a discharge end extending into said chamber in atomizing relation with the discharge end of said liquid tube, and a delivery tube projecting into said chamber 40 into receiving relation with the atomizing ends of said liquid and air tubes.

4. In an atomizer, a reservoir, a trap chamber and a partition located to prevent 45 communication between said chamber and reservoir except near the base of the latter, a liquid tube having an intake end opening to the liquid in said reservoir and having a discharge end extending into said chamber, an air tube extending through said reservoir 50 and having a discharge end extending into said chamber in atomizing relation to the discharge end of said liquid tube, and a delivery tube projecting into said chamber into receiving relation with the atomizing ends 55 of said liquid and air tubes, said delivery tube having a trap portion for catching liquid drippings and preventing outflow thereof through said delivery tube.

5. An atomizer comprising in combination, liquid and air tubes having their discharge ends in atomizing relation, a delivery tube in receiving relation with said atomizing ends and having a perforated trap in advance of the atomizing ends of 60 said tubes with respect to the direction of

flow, a reservoir for supplying said liquid tube, and means for guiding the discharge from said trap to said reservoir.

6. An atomizer comprising in combination, liquid and air tubes having their discharge ends in atomizing relation, a delivery tube in housing and receiving relation with the atomizing ends of said tubes and having a perforated trap in advance of the atomizing ends of said tubes with respect 75 to the direction of flow therethrough, a reservoir for supplying said liquid tube, and means for guiding the discharge from said trap to said reservoir.

7. An atomizer comprising in combination, liquid and air tubes having their discharge ends in atomizing relation, a delivery tube in housing and receiving relation with said atomizing ends and having an annular flared trap in advance of the atomizing ends 85 of said tubes with respect to the direction of flow therethrough, said trap having perforations therein opening rearwardly of the direction of flow, a reservoir for supplying said liquid tube, and means for guiding the 90 discharge from said trap perforations to said reservoir.

8. An atomizer comprising in combination, a reservoir of a diameter and length for containing a predetermined maximum 95 quantity of liquid, a trap chamber, a partition tube extending axially of said reservoir and opening near the base of the latter and axially thereof, thereby preventing the liquid from entering said partition tube in 100 any position the atomizer may occupy, a normally open delivery tube in open communication with said reservoir through said partition tube, an air tube extending through said reservoir and partition tube 105 and into delivering relation with said delivery tube, and a liquid tube in said partition tube and in atomizing relation with said air tube and opening to said reservoir axially and near the base thereof and therefore out of reach of the liquid in any position the atomizer may occupy except an operative atomizing position.

9. An atomizer comprising in combination, a unitary body having at its base end a reservoir of a cross section and length for containing a predetermined maximum quantity of liquid such as would dispose the level of the liquid substantially below the longitudinal axis of said reservoir when said body is 110 in a horizontal position, said body having a trap chamber in contiguous end to end relation with said reservoir and the front end of said reservoir joining the rear end of said chamber, a partition tube extending 115 axially through said reservoir and in spaced relation with the annular wall of the latter toward and opening near the base of said reservoir and of sufficiently reduced diameter to be above the liquid level in said reservoir 120

115

120

125

130

voir when said body is in a horizontal position, whereby when said body is in an inverted position the liquid will be held between the partition tube and said reservoir 5 with the juncture of said reservoir with said chamber as the bottom, a delivery tube extending axially in and in spaced relation with the walls of said chamber and toward and in aligned relation with said partition 10 tube and therethrough in open communication with said reservoir, whereby any liquid entering or gaining access to said chamber will be trapped against egress through said delivery tube, an air tube discharging toward said delivery tube, and a liquid tube in said partition tube having its intake end sufficiently above the liquid level in said reservoir when said body is in a horizontal position to prevent entrance of the liquid into 15 said liquid tube, and the discharge end of said liquid tube being in atomizing relation with the discharge end of said air tube.

10. In an atomizer, a trap chamber and a reservoir in integral end to end relation and 20 said reservoir having a base opening, a partition tube forming an extension of said chamber from the juncture of the latter with said reservoir and extending axially 25

of the latter and into said opening, an air tube extending through said opening into 30 said partition tube in spaced relation thereto, and closure means for said opening supporting said air tube and the free end of said partition tube.

11. An atomizer comprising in combination, liquid and air tubes having their discharge ends in atomizing relation, a normally open delivery tube housing the discharge ends of said liquid and air tubes, and a reservoir structure for supplying liquid 40 to said liquid tube and including a trap for preventing liquid from discharging through said normally open delivery tube irrespective of the position of said atomizer.

12. An atomizer comprising in combination, liquid and air tubes having their discharge ends in atomizing relation, a normally open delivery tube in housing relation to said discharge ends, a reservoir for the liquid sent through said liquid tube, and 50 said delivery tube having a trap for preventing discharge of liquid therethrough.

In testimony that I claim the foregoing as my own, I hereby affix my signature.

JOHN H. BEYNON.
